UNITED STATES PATENT OFFICE.

ETTIE L. SHANE, OF CARNEGIE, PENNSYLVANIA.

INSTEP-SUPPORT.

1,072,878.

Specification of Letters Patent.

Patented Sept. 9, 1913.

Application filed June 28, 1912. Serial No. 706,420.

To all whom it may concern:

Be it known that I, ETTIE L. SHANE, a citizen of the United States of America, residing at Carnegie, in the county of Allegheny and State of Pennsylvania, have invented certain new and useful Improvements in Instep-Supports, of which the following is a specification, reference being had therein to the accompanying drawing.

10 This invention relates to an instep support, and the primary object of my invention is to provide a device that can be easily and quickly connected to the arch of a shoe sole to support the instep and prevent the same from breaking down.

A further object of this invention is to provide an instep support that is simple in construction, durable, and highly efficient for the purposes for which it is intended.

20 With the above and other objects in view, the invention resides in a novel construction, to be hereinafter specifically described and then claimed.

Reference will now be had to the drawing, wherein there are illustrated the preferred embodiments of my invention, but it is to be understood that the structural elements are susceptible to such changes as fall within the scope of the appended claim.

30 In the drawing, Figure 1 is a side elevation of the preferred form of instep supports. Fig. 2 is a cross sectional view of the same, and Fig. 3 is a perspective view of a modified form of the support.

35 A support in accordance with this invention comprises a block 1 that has a rear vertical wall 2 adapted to fit against the front wall of a shoe heel 3. The block 1 tapers from the vertical wall 2 to the front edge thereof, said block providing a compound curved upper surface 4 that fits against the arch 5 of a shoe sole 6. The block 1 has concave side walls and the bottom of said block has a convex surface 7 that

projects slightly below the plane of the sole 6 and the heel 3. The convexed surface 7 which projects beyond the plane of the sole 6 is employed in case of a broken down arch of an old shoe as it necessitates greater pressure to restore an arch to normal position 50 and which pressure could not be obtained if the tread surface of the block were in the same plane as that of the tread surface of the heel and sole.

As illustrated in Figs. 1 and 2, the sides 55 of the block 1 are provided with angle staples 8 and these staples are held in engagement with the sides of the arched portion of the shoe sole by nails 9 that are driven into the sole.

In Fig. 3 of the drawing, there is illustrated a modification, wherein the block 10 has a flat bottom surface 11 and the concave sides of said block are provided with staples 12 to which are connected straps 13 65 and 14, the strap 13 having a buckle 15 whereby the ends of the straps can be connected over the shoe.

What I claim is:—

An instep support comprising a block 70 having the rear portion squared and its forward portion tapering, the upper and lower faces of said tapering portion being reversely curved with respect to each other, said block adapted to engage the arched 75 portion of a shoe sole, said curved lower face projecting beyond the plane of the lower surface of the heel and sole and staples carried by the sides and projecting above the block and providing passages for the entrance of holdfast devices into the shoe sole for connecting the block therewith.

In testimony whereof I affix my signature in the presence of two witnesses.

ETTIE L. SHANE.
